UNITED STATES PATENT OFFICE.

WALTER R. SCHINDLER, OF LONG BEACH, CALIFORNIA.

PLANT-CAP-APPLYING DEVICE.

1,357,523.

Specification of Letters Patent.

Patented Nov. 2, 1920.

Application filed February 24, 1920. Serial No. 360,662.

To all whom it may concern:

Be it known that I, WALTER R. SCHINDLER, a citizen of the United States, residing at Long Beach, in the county of Los Angeles 5 and State of California, have invented a new and useful Plant-Cap-Applying Device, of which the following is a specification.

My invention relates to a device for applying plant protecting caps and is more particularly directed to a device for inserting flanged plant caps into the ground and packing earth over the flange to retain the cap in position.

The object of the invention is to provide 15 a device by which a flanged plant cap is forced into the ground with its flanged portion below the surface and to provide means for packing earth over the flange to maintain the cap in position.

Another object is to provide a means for 20 packing earth upon the cap flange and automatically applying packing pressure thereto.

Various other objects and advantages will 25 be more fully apparent from the following description of the accompanying drawings, which form a part of this disclosure and which illustrate a preferred form of embodiment of the invention.

Of the drawings:

30 Figure 1 is a side elevation of the device.

Fig. 2 is a vertical section, showing the cap applied over a plant, previous to being forced into the ground.

Fig. 3 is a partial vertical section, showing 35 the cap forced into the ground.

Fig. 4 is a similar vertical section, showing the final operation of packing the earth over the cap flange.

Fig. 5 is a plan section on line x^5-x^5 of 40 Fig. 1.

With reference to the drawings, the device comprises two tubular casings 1-2, the outer casing 1 having upwardly and inwardly projecting arms 3 secured to a collar 4, and the 45 inner casing 2 being concentrically positioned within the outer casing, and having upwardly and inwardly projecting arms 5 as extensions of a spider member 6 which is secured on the lower end of a center rod 7 by 50 having a screw threaded engagement therewith and locked in place by a lock nut 8. The rod 7 extends upwardly through a central bore in the collar 4 and has an elongated slot 9 in which engages a transverse pin 10 secured to the collar 4. A coil spring 11 surrounds the rod 7 above and contacts with

the collar 4, the upper end engaging a washer 12 which is prevented from upward movement on the rod, by a transverse pin 13. The spring is normally under tension and 60 maintains the parts in the position shown in Fig. 2 with the lower flanged or flared peripheral edge 14 of the outer casing 1, extending below the lower edge of the inner casing 2.

A freely rotatable hand grip 15 is positioned on the upper portion of the rod 7 between washers 16-16, maintained against displacement by transverse pins 17-17, and a handle 18 is secured to the top of the rod. 70

The plant cap 20, which may be of any form which provides a circular flanged bottom edge 21, is positioned over the plant, and the device placed over it as shown in Fig. 2. A downward pressure applied to the handle 75 18 causes the inner casing 2 to move downward, its lower edge engaging the cap flange 21 and forcing the cap into the ground, as shown in Fig. 3. During this straight downward movement of the inner casing the outer 80 casing, by its contact with the ground, will remain stationary, this relative movement being provided for by the pin and slot connection 9-10 which also limits the downward movement of the inner casing so that 85 all caps positioned by the device will be forced into the ground to a uniform depth. This pin and slot connection also prevents a rotation of one casing relative to the other.

With the cap in place, as shown in Fig. 3, 90 the pressure on the handle 18 is gradually released and at the same time the entire device is given a rotary movement. This causes the flared lower edge of the outer casing 1, to force over the submerged flange of the cap, the spring 11 forcing the outer casing downwardly as said casing, by its rotary movement cuts into the earth. As the outer casing 1 packs the earth over the cap flange the downward pressure on the handle 18 is 100 released to allow the inner casing 2 to be raised by the spring 11, to normal position, completing the operation. (See Fig. 4). The purpose of the grip 15 is to afford a hand-hold for steadyng the device during 105 the rotary earth packing movements.

From the above, it will be seen that I have provided a device for positioning and anchoring plant protecting caps in the ground, which first is functioned to engage the cap 110 flange and force the cap edges below the surface, and then is rotated, or oscillated, to

force the adjacent earth over the cap flange and pack it firmly thereon to maintain the cap in place.

This device is efficient and simple, both the 5 cap inserting and earth packing functions being performed by the manipulation of a single handle.

I claim—

1. A plant cap applying device, combining an inner casing, an operating rod secured thereto, an outer casing slidable on said rod and having a flanged lower peripheral edge, and means yieldingly maintaining the outer casing in normal position on 15 the rod.

2. A plant cap applying device, combining an inner casing, an operating rod secured thereto, an outer casing slidable on said rod and provided with a flared lower 20 peripheral edge, and means yieldingly maintaining the outer casing in normal position on the rod.

3. A plant cap applying device, combining an inner casing of uniform diameter, 25 an operating rod secured thereto, an outer casing slidable on said rod and provided with a flared lower peripheral edge, and means yieldingly maintaining the outer casing in normal position on the rod with its

lower edge below the lower edge of the inner 30 casing.

4. A plant cap applying device, combining an inner casing, an operating rod secured thereto, a flanged outer casing slid- 35 able on said rod, means yieldingly maintaining the outer casing in normal position on the rod, and means for limiting the move- ment of the outer casing.

5. A plant cap applying device, combining an inner tubular casing, an operating 40 rod secured thereto, an outer tubular casing slidable on the rod, means preventing relative rotation of the casings, and means 45 yieldingly maintaining the outer casing in normal position on the rod.

6. A plant cap applying device combining two concentrically positioned tubular casings longitudinally movable relative to each other and rotative as a unit, means yieldingly maintaining the casings in nor- 50 mal position, and a single operating handle secured to one casing.

Signed at Brawley California this 11 day of February 1920.

WALTER R. SCHINDLER.
